UNITED STATES PATENT OFFICE.

FRANCIS DUPLAN, OF ARCUÉIL, FRANCE.

DISTILLATION AND CARBONIZATION RETORT AND PROCESS OF OPERATING THE SAME.

Application filed October 15, 1923, Serial No. 668,655, and in France October 20, 1922.

The present invention is an improved retort or furnace for the distillation and carbonization of all kinds of substances and matters, and an improved process of distillation and carbonization by means of which the evolved vapors or gases are not only prevented from condensing in the heating chamber but are also prevented from being dissociated, decomposed or otherwise injuriously altered during the distillation. Briefly, this is accomplished by making the heat permeability of the top of the retort chamber such that during the distillation there will be no thermic reaction of the under-surface of the top upon the vapors or fumes given off by the matter under treatment. In other words, by supplying heat from below and rapidly carrying off a predetermined amount of heat by radiation through the top of the heating chamber, the temperature in the upper portion of such chamber during the distillation will be maintained at a point which will not cause the gases to condense or to be injuriously affected.

In practicing the invention I make use of a furnace or retort which has a lower or body portion of the coke-oven type but which has a special top to provide for the proper loss of heat to accomplish the desired result. By coke-oven type I mean a furnace which has a sole-plate heated only from below and arranged between side walls usually of masonry so as to permit of the minimum loss of heat. In the preferred form of top for the heating chamber or retort, I employ spaced metal plates separated by a predetermined interval which depends upon the temperature to be maintained in the top portion of the heating chamber. In such a retort the heat must pass up through the sole-plate, the matter under treatment, the atmosphere of the chamber and the special top before it reaches the outer atmosphere. With a known temperature at the sole-plate and a known temperature of the external air, the successively decreasing temperatures of the matter under treatment and of the different parts of the retort through which the heat passes, can be readily calculated after the normal rate of operation of the retort has been decided upon. These heat losses depend upon the nature of and upon the thickness of the several layers traversed by the heat and they can be calculated in advance by the use of

the laws for the transmission of heat. If the distance separating the two metal plates forming the top wall of the heating or distillation chamber is conveniently adjusted, 60 it will be easy to obtain for the under surface of such top wall in contact with the atmosphere of the chamber, the required temperature so that there will be no condensation, dissociation or chemical alteration of 65 the vapors or gases evolving through the distillation, the carbonization or the pyro-generation of the matter under treatment.

The accompanying drawings illustrate a retort which is one of many possible embodiments of the invention, and by means of which the new process may be carried out.

Fig. 1 is a longitudinal section taken on line A—A of Fig. 2.

Fig. 2 is a cross section taken on line 75 B—B of Fig. 1.

In the drawings 1 denotes the heating or distillation chamber which is bounded at its bottom by a sole-plate 2, at its sides by an upright wall 3 and at its top by a heat-dissipating cover preferably composed of arched metal plates 4 and 5 separated by an air space 6. At the front end of the retort wall 3 is an opening 7 for the introduction and removal of the substance or matter to be treated, the latter being placed either directly on the sole-plate or in a suitable receptacle 8 made of metal or other material and supported on the sole-plate. The vapors or gases evolved during the treatment 80 are exhausted through a pipe 9 preferably in the wall 3 at the rear end of the retort.

While the sole-plate may be heated from below by any suitable means, I have illustrated it heated by the combustion of gases 95 which are fed through ducts 10 and 11 into channels 12 and 13 provided with burner ports 14 and 15. The latter open into combustion flues 16 that are immediately beneath the sole-plate 2. 17 denotes flues for 100 the escape of the products of combustion and 18 air inlet ducts provided in the walls of these flues and used for the recovery of part of the heat. These ducts 18 are connected with the duct 11 by suitable passages 105 not shown. 19 and 20 designate sight-openings provided in the ducts 12, 18 and 17.

The upright wall 3 of the heating chamber is preferably composed of cast-iron and is surrounded by a body of sand 21 which in turn is surrounded by brick-work 22 rising from the masonry in which the burners

and recuperators are mounted as shown in Fig. 2. The upright walls of the retort or furnace are thus composed of a cast-iron inner portion spaced from a masonry outer portion and a filling of sand or other equivalent poor conductor of heat; and hence the heat generated is concentrated on the sole or bottom of the distillation chamber. The masonry outer wall member 22 as seen in Fig. 2 rises to a height above the cast-iron inner wall member 3, and the latter is made in sections, the lower one being permanent and the upper one 25, which spaces apart the top or cover plates 4 and 5, being removable and replaceable by another of a different height. The height of this wall section or extension 25 is selected for the purpose of spacing the plates 4 and 5 apart to a greater or lesser extent and hence controlling the heat permeability of the retort top.

The opening 7 may be closed by a hollow door 23 which may be mounted to slide vertically in suitable guideways 24 in the front portion of the side wall, or otherwise mounted.

If desired the under face of the plate 4 may be covered with a refractory coating (not shown) to prevent the products of distillation from coming into contact with the hot metal.

While the side walls are preferably made as shown, they may be of other constructions, and this is also true of the special top for the heating chamber although I preferably employ spaced plates which are separated from each other by an interval which will vary according to the temperature it is desired to maintain at the top of the heating chamber. The space intervening the plates 4 and 5 may be merely a dead air space; or it may contain any fluid at rest or in continuous circulation; or it may be filled with a suitable heat insulating material that will give the top the desired permeability to heat.

In carrying out the new process, the matter or substance to be treated is placed in the lower part of the heating chamber either directly upon the sole-plate or in a receptacle thereon. The sole-plate is heated to the proper temperature according to the material under treatment, and the gases or vapors given off from the material are drawn out of the heating chamber through the outlet thereof. Since the heat is supplied only through the sole-plate it must rise vertically through the retort, and since the heat permeability of the top or cover is made to permit of a predetermined loss of heat by radiation, there will be maintained in the top of the heating chamber a temperature which is between that at which the evolved gases or vapors will be condensed and that at which they will be decomposed, disso-

ciated or otherwise injured. Such temperature for the top of the heating chamber will, of course, depend upon the material being treated and the distillation products being recovered; but the special top or cover for the heating chamber will permit of the proper loss of heat by radiation so that the desired temperature is maintained in this portion of the retort. I thus regulate the temperature by the loss of heat through the top of the retort rather than by regulating the amount of heat supplied at the bottom thereof. It will of course be understood that if the gases to be recovered are given off at a certain temperature, it will be necessary to have a higher temperature at the sole-plate or bottom of the heating chamber in order for the heat to penetrate to the center of the mass of material being treated, but since the top of the heating chamber is cooled by the radiation of heat through the retort top the gases as they are evolved will rise to zones of lower temperature and will not be injuriously affected in their passage to the outlet.

I claim:

1. In a process of operating a retort, having a distillation chamber with a sole-plate and with a heat dissipating top, and with means for heating said chamber through said sole-plate from below the same, and in which carbonaceous material is being destructively distilled; supplying heat to said chamber through said sole-plate and regulating the loss of heat through said top so that the temperature in the upper portion of said chamber will be such that there will not be any substantial condensation, dissociation or chemical alteration of the evolved gases in said upper portion.

2. A distillation and carbonization retort comprising a sole-plate, heating means beneath the latter, side walls rising from the sole-plate and a heat dissipating top forming in connection with the side walls and sole-plate a heating chamber, said top including vertically spaced superposed substantially horizontal plates and means for varying the vertical distance between the plates to permit of a predetermined loss of heat by radiation so that during the distillation of the matter under treatment, the portion of the chamber immediately beneath said top will be maintained at a temperature at which there will be no substantial condensation, dissociation or chemical alteration of the vapors evolved, because of the radiation of heat through said top.

3. A distillation and carbonization retort including a sole-plate, heating means beneath the latter, a sectional wall surrounding the sole-plate and comprising upper and lower sections, the upper section being readily removable for interchange with other sections of different heights, and a top composed of

upper and lower plates spaced apart by said upper removable section of the wall, where- 4. A structure as specified in claim 3; 10
by the heat permeability of the retort top together with an outer wall around and
may be conveniently adjusted to maintain spaced from the sectional wall and rising
5 the underside of the lower plate of the top to a height above the latter, and a filling of
at such temperature that there will be no sand between said outer wall and said sec-
substantial condensation, dissociation or tional wall. 15
chemical alteration of the vapors evolved
from the matter under treatment.

In testimony that I claim the foregoing as
my invention, I have signed my name.

FRANCIS DUPLAN.
